CLAIM

The ornamental design for a travel bottle assembly, as shown and described.

DESCRIPTION

FIG. 1 is rear elevation view of a travel bottle assembly, showing our new design;

FIG. 2 is a top plan view thereof;

FIG. 3 is a bottom plan view thereof;

FIG. 4 is a front elevation view thereof;

FIG. 5 is a right side elevation thereof;

FIG. 6 is a left side elevation view thereof;

FIG. 7 is a front, left side, and bottom perspective view thereof;

FIG. 8 is a front elevation view of our new design for a travel bottle assembly shown separated for clarity of disclosure;

FIG. 9 is a front, right side and top perspective view of FIG. 8;

FIG. 10 is a front, right side and bottom perspective view of FIG. 8;

FIG. 11 is a rear and bottom perspective view of our new design for a travel bottle assembly shown with top and bottom portions removed for clarity of disclosure; and,

FIG. 12 is a front and top perspective view of FIG. 11.
